CHILD'S FORK OR SIMILAR ARTICLE

Natacha Brooks, New York, N. Y.

Application January 24, 1952, Serial No. 18,207

Term of patent 7 years

(Cl. D44—29)

To all whom it may concern:

Be it known that I, Natacha Brooks, a citizen of the United States of America, residing in New York city, county of New York, and State of New York, have invented a new, original, and ornamental Design for a Child's Fork or Similar Article, of which the following is a specification, reference being had to the accompanying drawing, forming part thereof, wherein,

I claim:

The ornamental design for a child's fork or similar article, substantially as shown.

NATACHA BROOKS.
